UNITED STATES PATENT OFFICE.

DAVID BLOOM, OF BERKELEY, CALIFORNIA.

RECEPTACLE-CLOSURE.

1,159,825.

Specification of Letters Patent.

Patented Nov. 9, 1915.

Application filed April 16, 1914. Serial No. 832,211.

To all whom it may concern:

Be it known that I, DAVID BLOOM, a citizen of the United States, and a resident of Berkeley, county of Alameda, and State of California, have invented certain new and useful Improvements in Receptacle-Closures, of which the following is a specification.

The invention relates to improvements in closures for receptacles such as jars, bottles and the like, in which fruit, vegetables or other products are to be preserved or contained.

The object of the invention is to provide a closure which will hermetically seal the receptacle and prevent the air from coming into contact with the material contained therein.

Another object of the invention is to provide a closure for receptacles which is held to its seat by a resilient element attached to the closure and engaging the side of the receptacle adjacent its mouth.

A further object of the invention is to provide a thoroughly sanitary closure which may be readily cleaned and from which the resilient element may be readily removed.

Another object of the invention is to provide an improved means for holding the resilient element to the closure.

Another object of the invention is to provide a closure which may be secured to the receptacle before the products therein are processed and has the quality of yielding slightly to allow the expanded air in the receptacle to escape as the air and contents expand under the action of heat during the processing operation.

The invention possesses other advantageous features which, with the foregoing, will be set forth at length in the following description where I shall outline in full that form of the invention which I have selected for illustration in the drawings accompanying and forming part of the present specification. The novelty of the invention will be included in the claims succeeding said description. From this it will be apparent that I do not limit myself to the showing made by said drawings and description, as I may adopt many variations within the scope of my invention as set forth in said claims.

Figure 1 is a vertical section of a jar showing the cover of my invention attached

thereto. Fig. 2 is a vertical section of a portion of the jar and closure of my invention, taken at right angles to the section shown in Fig. 1. Fig. 3 is a perspective view of the under side of the closure of my invention from which the resilient element has been removed. Fig. 4 is a plan view from below of the closure of my invention. Fig. 5 is a side view of the resilient element which is adapted to be attached to the closure. Fig. 6 is a cross section of the resilient element.

In the method of preserving food products, by hermetically sealing them in receptacles, the products are placed in the receptacles and heated or processed to drive out the air, and the closures are then applied. As the contents and receptacle cool, the air and contents in the receptacle contract, thereby seating the closure more tightly and forming a partial vacuum in the receptacle.

By the use of the closure of my invention, the receptacles are covered and closed before the contents are processed so that the contents will not come in contact with the steam in the heating chamber nor will the drippings from the condensation of the steam fall into the receptacles and contaminate the contents. The closure of my invention is held to its seat by means of a tension member or resilient element attached to the closure, so that the receptacle is sealed against ingress of air as soon as the closure is applied. During the processing operation, however, the pressure in the interior of the receptacle is increased, and this pressure raises the closure slightly and allows the excess air to escape, so that upon cooling a partial vacuum is formed within the receptacle.

The jar or receptacle 2 with which the closure of my invention is used is provided on its inner surface adjacent the mouth with oppositely disposed inclined grooves 3, which open at the upper ends at the top of the receptacle and which are adapted to be engaged by the ends of the resilient or tension element 4 secured to the under side of the closure or cover. When the cover is placed on the receptacle and rotated, the ends of the tension element engage the inclined grooves and are forced downward, flexing the spring or tension element and thereby holding the closure tightly to its seat against the top of the receptacle. Ar. 110

ranged between the closure and the upper edge of the jar is a gasket or packing 5, which is partially seated in an undercut annular groove 6 formed in the depending annular wall 7, which seating prevents the gasket from falling away from the cover, when the cover is separate from the receptacle. The closure is preferably formed of glass or other vitreous material which may be readily cleaned after use.

10 Formed on the under side of the body portion A of the closure and preferably centrally thereof, is a depending boss 8 which is provided with a transverse groove 9 in which the tension member 4 is seated. The 15 groove 9 is formed with inwardly sloping sides 12, forming a dove-tailed groove which is wider at the base than at its open face. The sides 12 of the groove preferably 20 meet the under surfaces of the boss 8 in smooth curves, so that no edges are presented which might cut or chip. The under surfaces 13 of the boss 8 preferably slope toward the base of the groove to increase the 25 effect of the curvature.

25 Seated in the dove-tailed groove is the tension or spring element 4 which is provided with complementarily sloping sides or edges 14, so that it seats firmly in the groove 30 and may not be displaced or pulled therefrom when the element is placed in tension. The tension element preferably consists of a strip of bamboo or similar material which possesses the desired resilient qualities and 35 which will not affect nor contaminate the food products within the receptacle. This bamboo strip is preferably cut away slightly at the ends so that it will readily engage in the inclined grooves in the jar.

40 The groove 9 is also preferably tapered transversely, that is, the side walls 12 converge toward one end of the boss, so that when the properly cut bamboo strip is inserted it comes to a seat in the proper position to properly engage the grooves in the 45 jar when the cover is placed on the jar. The juncture between the side walls of the groove 9 and the outer side walls of the boss 8 are preferably formed on a smooth 50 curve, in order to strengthen that portion of the boss and prevent any chipping which might occur if the juncture occurred at a sharp line. The bottom 15 of the groove also preferably slopes downward toward the 55 narrow end of the groove, forming the groove larger in both dimensions at one end than it is at the other. The bamboo strip is also preferably tapered so that when it is inserted in the groove it comes to its seat at 60 the proper position.

In order to facilitate the insertion of the bamboo strip into the groove 9, I have formed a wide rib 16 between the boss 8 and the wall 7 in line with the groove and at the 65 wide side thereof. The surface 17 of the rib

is flush with the bottom of the groove and the bottom of wall 7, and by using this surface 17 as a guide, the strip may be readily inserted in the groove. Closures of this nature are designed to be repeatedly used, 70 season after season, and a new tension element may be inserted each time the closure is used in order that the pressure of the closure against the jar may be insured, but I have not found this to be necessary. 75 When the closure is removed from a filled jar, the bamboo strip may be removed, and the closure, since it presents no inaccessible portions, may be readily and thoroughly cleaned.

80 I claim:

1. A receptacle closure comprising a body portion, a boss on the under side of said body portion having a dove-tail shaped tapered groove formed therein and a resilient tapered element seated in said groove.

2. A receptacle closure comprising a body portion, a boss on the under side of said body portion having a transverse groove formed therein, the side walls of said groove sloping outwardly toward the base of said groove and being converging and a resilient element seated in said groove.

3. A receptacle closure comprising a body portion, a boss on the under side of said body portion having a transverse groove formed therein, the side walls of said groove being inclined and converging toward one end of the groove and said groove being shallower at the narrow end than at the 100 broad end and a resilient element seated in said groove.

4. The combination with a receptacle closure having a dove-tail shaped tapered groove in its under face, of a correspondingly shaped resilient element seated in 105 said groove.

5. A receptacle closure comprising a body portion, a boss on the under side of said body portion having a groove therein, a resilient member adapted to be inserted in 110 said groove, and a guide for the insertion of said member.

6. A receptacle closure comprising a body portion, a boss depending from the under side of said body portion, provided with a transverse groove and a rib on said under side having an upper face forming a continuation of the base of said groove.

7. A receptacle closure comprising a body 120 portion, an annular wall depending from said body portion, central boss depending from said body portion having a transverse groove therein, and a rib between said boss and wall, the face of said rib being flush 125 with the bottom of said groove and the face of said wall.

8. A receptacle closure comprising a body portion, a boss on the under side of said body portion provided with a transverse 130

groove having overhanging walls, said groove being tapered in one direction and a correspondingly tapered resilient element seated in said groove.

5 9. The combination with a receptacle provided with oppositely disposed inclined grooves in its mouth, of a closure for said receptacle having an upwardly expanding tapered groove in its lower face and a resilient element seated in said groove and

having its ends in engagement with said inclined grooves.

In testimony whereof, I have hereunto set my hand at San Francisco, California, this 26th day of March 1914.

DAVID BLOOM.
